United States Patent Office

Des. 201,162
Patented May 18, 1965

201,162

BOILER

Sam N. Craig and Franklin L. Van Reed, Reading, Pa.,
assignors to Orr & Sembower, Inc., Reading, Pa., a
corporation of Pennsylvania

Filed Dec. 5, 1960, Ser. No. 63,118

Term of patent 14 years

(Cl. D76—1)

FIGURE 1 is a front elevation of a boiler embodying our new design;

FIGURE 2 is a rear elevation thereof;

FIGURE 3 is a side elevation thereof looking toward the right as viewed in FIGURE 1;

FIGURE 4 is an elevation of the side of the boiler opposite to the side shown in FIGURE 3; and

FIGURE 5 is a top plan view thereof.

The dominant features of our new design are shown in full lines.

We claim:

The ornamental design for a boiler, substantially as shown and described.
